APPARATUS FOR SHAPING FIBRE LAPS IN A LAP-FORMING MACHINE

Ryuhei Kawazura, Motoyama-cho, Higashinada-ku, Kobe, Kazuo Fujii, Fuse, and Masaru Fujiwara, Yoshida-cho, Hyogo-ku, Kobe, Japan, assignors to Kanegafuchi Spinning Co., Ltd., Tokyo, Japan, a joint-stock company of Japan

Application July 16, 1956, Serial No. 598,197

Claims priority, application Japan July 20, 1955

3 Claims. (Cl. 242—55.1)

This invention relates to an apparatus for shaping fibre laps in a lap-forming machine.

It is a conventional feature of a lap-forming machine to include a pair of fluted lap-forming rollers and a lap roller which is rotated on and by contact with the rotating lap-forming rollers and upon which is wound fibre material continuously fed through a plurality of calender rollers. The journals of the lap-roller are engaged with a pair of rack-bars or, alternatively, a press-roller positioned on and in contact with the lap is supported by a pair of rack-bars whose upward movement caused by the growth of the lap in diameter is restrained so that the lap is pressed downwardly against the surfaces of the lap-forming rollers in order to ensure the formation of a tightly rolled lap. When the lap is formed on the machine it is ejected and a fresh empty lap roller is delivered to the lap forming position in place of the ejected lap. The operation may be cycled automatically and continuously.

Because of the fact that the lap is rotated for only a short while on the fluted lap-forming rollers after being completed and before being ejected, the lap-end or loose end of the lap broken from the unlapped fibre material is not satisfactorily wrapped around the lap and furthermore the lap itself lacks of tightness or density. Particularly when the machine is continuously and automatically operated the drawback is more noticeable so that the lap-end and the surface of the lap are loosened and disordered in the subsequent handling thereof, often causing production of a large quantity of waste fibre material.

It is a general object of the present invention to provide an apparatus for satisfactorily shaping fibre laps formed on the main lap-forming machine, to completely wrap the lap-end around the lap and tighten it satisfactorily.

Another object of this invention is to provide an apparatus for the purpose specified which may be continuously and automatically operated in cooperation with and driven from the main lap-forming machine.

According to this invention, a pair of grooved lap shaping rollers which rotate at all times in the same direction as that of a pair of fluted lap rollers in the main machine and upon which is to be ejected a lap completed or formed on the main machine are loosely mounted on a pair of respective arms pivoted on an axle. Means are provided to connect the arms to a vertically moving antifriction rack bar for turning the arms about said axle and thereby swinging or inclining the grooved rollers forwardly and back to the original, normal or horizontal position. A frame bar is connected to said arms in such a manner that it prevents the lap on the grooved rollers in the normal position from rolling out, while it permits the lap to roll out from the grooved rollers when they are forwardly swung.

Other objects and features of the invention will be

2

come apparent from the following description and the accompanying drawings which show one embodiment of the present invention.

In the drawings:

5 Fig. 1 is a fragmentary side view of a lap-forming machine associated with a lap-shaping apparatus according to this invention showing the normal state of operation of the apparatus.

10 Fig. 2 is a view similar to Fig. 1 but showing the state where the grooved lap-shaping rollers are swung or inclined forwardly to roll the shaped lap out thereof.

15 Fig. 3 is a view similar to Fig. 1 but showing the state where a lap completed on the main machine has been ejected therefrom onto the grooved lap-shaping rollers.

Fig. 4 is a plan view of Fig. 1 omitting the lap on the grooved rollers.

Referring to Figs. 1 and 4, the main lap forming machine comprises a pair of rotating fluted lap-forming rollers 1 and 1'. Indicated with the numeral 2 is a rotating press-roller which acts to press either the lap-roller 3 or the lap L downwardly so that the lap L is pressed upon the surface of the rollers 1 and 1'. The shaft 4 of the press-roller 2 is rotatably supported by 20 a pair of rack bars 5, 5' whose upward movement caused by the growth of the lap in diameter is restrained for the well known purpose and by any well known means. The machine is so constructed that when the lap is formed or completed the braking action on the rack bars 30 5, 5' is released and the lap is ejected and a fresh empty roller is delivered to the lap forming position in place of the ejected lap. These features are rather conventional features of a lap-forming machine and are not the essence of this invention, and therefore details thereof are omitted from the drawings. However, for example, reference may be made to those shown and described in our pending application Serial No. 410,226 filed February 15, 1954. The apparatus of this invention may be applied to any machine having the features mentioned.

40 In front of the fluted lap-forming rollers 1, 1' there are provided a pair of front and rear grooved lap-shaping rollers 6, 6' (hereinafter abbreviated as shaping rollers) whose journals are loosely supported at both ends by a pair of arms 7, 7' which are symmetrically and loosely 45 fitted on a horizontal axle 8 extending between and connected to frames 9, 9' of the machine.

A pulley 10 formed integrally with a gear 11 loosely fitted adjacent one end of the axle 8 is driven from a 50 pulley 12 secured on the axle of the rotating fluted lap forming roller 1. Gears 13 and 13' secured to the respective axles of the shaping rollers 6, 6' mesh with said gear 11 so that the shaping rollers 6, 6' are at all times rotated in the direction indicated by the arrows (Figs. 1 and 3).

55 Adjacent the point at which the shaping roller 6' is mounted on the arm 7 there is provided on said arm 7 a longitudinal extension b and a downwardly projecting hook member c. A pair of symmetrical upward projections a are provided on the respective arms 7 and 7' adjacent the point at which the shaping roller 6' is mounted on the respective arms 7 and 7'. A downward projection d is provided at the opposite end of the arm 7.

On the upper part of the rack bar 5 there is provided a lug 14 engageable with a pawl 15 pivoted at 16 on one 60 end of an L-shaped rod 17 pivoted at 18. A spring 19 is connected at its one end with the pawl 15 and at the other end with the rod 17 so as to normally spring-press the end of the pawl 15 against a pawl stopper 20 pivoted on the rod 17. The pressed contact of the stopper 20 to the end of the pawl is assisted by a plate spring 21 mounted on the rod 17. The upper end of a latch 22

pivoted at 23 is held against the lower end of the L-shaped rod 17 by means of a spring 24. On said latch 22 there is provided a lug 25 which normally engages the hook 26 of the member c on the arm 7, and by said engagement the arms 7 and 7' are normally kept horizontal. Indicated by reference numeral 27 is a pinion engaged with the rack on the rack bar 5. A cam 28 is secured to the shaft 29 of the pinion 27. At one end of a lever 30 having its fulcrum at 31 there is mounted a roller 32 which is in contact with the surface of the cam 28. The other end of the lever 30 is pivotally connected at 33 with the lower end of a link 34 whose upper end is pivotally connected at 35 with the extension b of the arm 7. The downward projection d of the arm 7 is connected by a spring 36 to the frame of the machine so that when the arm 7 is released from the latching and the roller 32 drops into the recess 37 on the cam 28 the arm 7 is swung downwardly and forwardly around the axle 8 by the force of the spring 36. This causes the forward swinging or inclination of the shaping rollers 6 and 6' so that the lap L rolls out thereof.

To prevent the lap L from rolling out when the shaping rollers 6 and 6' are in normal position and to prevent the lap ejected from the main lap-forming machine from jumping off the shaping rollers, a frame bar 38 is pivoted at its ends to the axles 39 respectively supported by the upward projections a on the arms 7 and 7'. The frame bar 38 is pivotally connected at both sides with the upper ends of a pair of links 40 whose lower ends are pivoted to side frames 9 and 9' at 41. It will be understood that when the arms 7 and 7' are swung the frame bar 38 is also swung downwardly to permit the lap to roll off the shaping rollers.

Indicated by reference numeral 42 is an adjustable stopper. When the pawl stopper 20 moves upwardly together with the pawl 15 and contacts the stopper 42 the latter will press the pawl stopper 20 downwardly so that the stopper 20 is disengaged from the pawl 15 as shown in Fig. 2 and the pawl 15 is made free. Therefore, the movement of the rack bar 5 is not transmitted to the L-shaped rod 17 and the rack bar 5 can move upwardly without restraint of the pawl 15. In this state, the rod 17 may be pulled downwardly to its original position by means of a spring 43 connected thereto.

The operation of the machine is as follows:

When a predetermined length of the fibre material is wound upon the lap roller on the fluted lap-forming rollers 1 and 1' the lap L is ejected onto the grooved shaping rollers 6 and 6' and a fresh empty lap roller 3 is delivered to the lap forming position in place of the ejected lap as shown in Fig. 3. This operation may be effected in any known manner, for example by means shown and described in our pending application Serial No. 410,226. The rack bars 5 and 5' immediately move downwards until the new lap formation is commenced. As shown in Fig. 1 by contacting with the grooved lap shaping rollers 6 and 6' rotating in the direction of the arrow, the lap-end or loose end of the lap is completely wrapped around the lap L and furthermore the lap itself is satisfactorily tightened and shaped.

Meanwhile, the rack bars 5 and 5' together with the press roller 2 move upwardly as the diameter of the new lap L increases. In the course of the upward movement the lug 14 on the rack bar 5 engages at a predetermined height, with the pawl 15 to lift or push up the latter as shown in Fig. 1. This causes the turning of the L-shaped rod 17 around the pivot 18 against the spring 43. Therefore, the lower end of the rod 17 engaging with the upper end of the latch 22 swings the latter to the left (in Fig. 2) around the pivot 23 against the spring 24 so that the lug 25 on the latch 22 is disengaged from the hook 26 to release the restraint on the arms 7 and 7'. At this point, the roller 32 drops into the recess 37 of the cam 28 which has been rotated in the direction of the arrow (Fig. 1) by the engagement

through the pinion 27 with the upwardly moving rack bar 5. Consequently the lever 30 is released from the control of the cam 28. The arm 7 now rendered free is turned clockwise around the axle 8 by the force of the spring 36 so that the shaping rollers 6 and 6' are inclined forwardly as shown in Fig. 2. It will be understood that the frame bar 38 is also swung downwardly so that the shaped lap L is rolled out downwardly from the shaping rollers 6 and 6'.

As the formation of the new lap L' proceeds the rack bar 5 with the pawl 15 and its cooperating members further moves upwardly. When the pawl stopper 20 engages the stopper 42 the former is turned counterclockwise around its pivot by the pressure of the latter as shown in Fig. 2 so that the pawl 15 is released from the pawl stopper 20 and freed from the lug 14. Consequently the L-shaped rod 17 is not affected by the upward movement of the rack bar 5. In other words, the rack bar 5 continues to move upwardly past the pawl 15. The L-shaped rod 17 is pulled downwardly by the spring 43 to the normal or original position. The latch 22 is also returned to the original position by the force of the spring 24. The cam 28 which has continued to rotate in the direction of the arrow (Fig. 1) again engages at its surface with the roller 32 so that the lever 30 and the link 34 are pulled down to the original position and the arms 5 and 5' are returned to the original horizontal position. It will be understood that the hook 26 again engages with the lug 25 on the latch 22 and the frame bar 38 is also swung back to the original position.

When a predetermined length of the fibre material is wound upon said new lap roller 3 or the lap L' is completed on the lap-forming rollers 1 and 1' it is ejected onto the shaping rollers 6 and 6' and the same operation hereinbefore described is repeated.

It will be understood that when the rack bar 5 moves downwardly the lug 14 thereon is not actuated by the pawl 15 because the latter is freely rotatable counterclockwise without obstructing the downward movement of the lug 14.

While the invention has been described in connection with a particular embodiment thereof, it is to be understood that we do not limit ourselves to the precise method and construction herein disclosed and the right is reserved to all changes and modifications coming within the scope of the invention or the limits of the appended claims.

We claim:

- An apparatus for shaping and discharging fibre laps in a lap-forming machine of the type having a pair of fluted lap-forming rollers, rack bars or rack heads, a lap roller which is rotated on and by contact with the rotating lap-forming rollers and upon which is wound fibre material, and means to eject the completed lap and deliver a fresh empty lap roller in place of the ejected lap, which apparatus comprises a pair of side frames, a pair of rotating grooved lap shaping rollers, a pair of arms on which said grooved lap shaping rollers are mounted, an axle on said side frames positioned in front of the lap-forming rollers on the lap-forming machine, said arms being rotatably mounted on said axle, the ejected lap being received on said lap shaping rollers for shaping, a latch pivoted on one of said side frames normally engaging one end of one of said arms to restrain the arms and the rotating shaping rollers in the horizontal position of said arms, a rod pivoted on one of said side frames having pawl and latch means mounted on its upper part engageable with one of the rack bars and said rod engageable at its lower end with said latch and rotated by the rack bar to disengage the latch from the arm to release said restraint as the rack bar moves upwardly, a spring connected between the other end of said one of said arms and one of said side frames to pull the said other end of said arms downwardly when said restraint is released so that said arms with said shaping rollers are turned around said axle to roll the shaped lap out of the

shaping rollers, adjustable abutment means on said lap-forming means abutted by said pawl and latch means when the rack bar moves further upwardly for disengaging said rod from the rack and permitting said latch to return to the active position engageable with said arm, cam and cam follower engaged by said rack bar, and linkage between said cam follower means and said arms for pulling said arms rearwardly to the original horizontal position where said latch engages the arm again to restrain the arms with the shaping rollers horizontal for receiving the next lap to be ejected from the lap-forming machine.

2. An apparatus as claimed in claim 1 in which said cam means comprises a cam rotatably mounted on said lap-forming machine and having a recess therein and having gear teeth thereon engaged with said rack bar, said cam follower means comprises a roller rolling on said cam, and said linkage comprises a lever pivoted on said lap-forming machine and having said roller rotatably mounted on one end thereof and a link pivotally connected between the other end of said lever and the said one end of one end of said arm, whereby when said roller drops into the recess on said cam, said lever is permitted to rotate to allow the forward turning of the arms and when said latch is to be brought into the original

10

15

25

position the roller engages the surface of the cam to rotate the lever in the opposite direction to pull the arm rearwardly to the horizontal position so that the arm is again engaged with said latch to restrain the arms with the shaping rollers in a horizontal position for receiving the next lap to be ejected from the lap-forming machine.

3. An apparatus as claimed in claim 1 and further comprising a frame bar having side portions and a transverse portion pivoted at the ends of said side portions to the said one end of said arms, and links pivoted between the said side frames and the middle of said side portions of said frame bar, whereby when said arms with the shaping rollers are kept horizontal said frame bar extends upwardly around the lap on the shaping rollers and when said arms are turned forwardly said frame bar is swung downwardly out of the path of the lap.
